HAIR SHAPING ATTACHMENT

Arthur Hillaire Madore, Los Angeles, Calif.

Application February 7, 1933, Serial No. 655,587

5 Claims. (Cl. 30—12)

My invention relates to an attachment for hair combs and the principal object of my invention is, to provide a relatively simple, practical and inexpensive device that may be conveniently applied to or removed from an ordinary hair comb and which device when properly positioned upon the comb may be conveniently used for effectively cutting, shaping and thinning the hair so that the same will conform to the shape of the head.

A further object of my invention is, to provide a hair cutting attachment for combs that utilizes as the cutting element, the standard forms of thin flexible double edged razor blades that are readily obtainable in the open market.

With the foregoing and other objects in view, my invention consists in certain novel features of construction and arrangements of parts that will be hereinafter more fully described and claimed and illustrated in the accompanying drawing in which:

Fig. 1 is a side elevational view of a comb and showing my improved cutting attachment in position thereupon.

Fig. 2 is an elevational view of the reverse side of the comb and showing the means utilized for clamping the cutting attachment to the comb.

Fig. 3 is a perspective view of a plate that forms the main body of the attachment and which plate receives and holds the razor blades.

Fig. 4 is an enlarged vertical section taken on the line 4—4 of Fig. 1.

Fig. 5 is an elevational view of a clamping plate that is positioned on the opposite side of the comb from the razor blade receiving and holding plate.

Fig. 6 is an elevational view of a conventional form of razor blade that may be used in my improved hair cutting attachment.

Fig. 7 is a perspective view of a modified form of the plate that receives the razor blades.

Fig. 8 is a perspective view of the parts that are detachably applied to the form of plate illustrated in Fig. 7 for the purpose of receiving the razor blades.

Fig. 9 is a perspective view of a further modified form of the razor blade receiving and holding plate.

Referring by numerals to the accompanying drawing and particularly to the construction illustrated in Figs. 1 to 6 inclusive, 10 designates a thin plate, preferably of metal, having a slightly rounded or convex outer face and a flat inner face and the width of which plate is slightly less than the length of the teeth of the comb to which the attachment is applied.

Formed integral with the ends of this plate and on the flat inner face thereof are transverse ribs 11 and projecting inwardly from said ribs on the flat face of the plate are short lugs 12 that are adapted to enter the notches in the ends of standard forms of thin double-edged razor blades of the type illustrated in Fig. 6.

The thickness of the ribs 11 and lugs 12 is approximately equal to the thickness of the razor blades.

Formed integral with and projecting upwardly from the intermediate portion of the flat inner face of plate 10, is an elongated lug 13 that is disposed in longitudinal alignment with lugs 12 and which lug 13 is adapted to enter the notches in the ends of a pair of razor blades that are positioned on plate 10.

Projecting upwardly from the flat inner face of plate 10 at points midway between the lugs 12 and the center lug 13, are short narrow posts 14 and 15 and formed through the upper portion of post 14, is an aperture 16 and formed in the upper portion of post 16 is an undercut notch 17.

A thin plate 18, preferably of metal, is adapted to be positioned on the side of the comb opposite from the side on which the blade carrying plate 10 is positioned and formed in the ends of plate 18 are notches 19 for the reception of those portions of the posts 14 and 15 that project beyond the teeth of the comb to which the attachment is applied.

A clamping member 20, preferably formed of metal, is provided at its ends with pintles 21 which when said clamp is applied for use, engage in the aperture 16 and notch 17 and the upper portion of said clamping member is curved to one side to form a hook 22 that engages over the upper edge of the comb to which the attachment is applied.

The comb to which the attachment is applied may be an ordinary metal comb or a comb of hard rubber, celluloid or the like that is plated with metal by any one of the standard metal coating methods now practiced and to apply the attachment to the comb a pair of thin flexible razor blades of the type illustrated in Fig. 6 are positioned on the flat face of plate 10 with the lugs 12 and 13 engaging in the notches in the ends of said blades.

The posts 14 and 15 project through the apertures in the centers of the blades and as said lugs and posts are located closer to one edge of the plate 10 than the other, the blades will be held on said plate with one cutting edge exposed.

and the opposite cutting edge inset from the adjacent edge of said plate.

The plate carrying the blades is now applied to one side of the comb, preferably that portion having the larger teeth with the posts 14 and 15 projecting between the teeth of the comb and plate 18 is now positioned on the opposite side of the comb from plate 10 with the posts 14 positioned in notches 19.

10 One of the pintles 21 on clamping plate 20 is now inserted through aperture 16 in post 14 and the other pinte is now engaged in the undercut notch 17.

The clamping plate is now swung upwardly so that the hook 22 engages over the back of the comb as illustrated in Figs. 2 and 4 and thus the attachment is clamped to the comb with the exposed cutting edges of the razor blades positioned a short distance above the points of the teeth, as illustrated in Figs. 2 and 4.

15 The comb with the attachment may now be used for cutting, shaping and thinning the hair either by running that portion of the comb carrying the attachment downwardly over the surface of the hair from the top of the head or by lifting part of the hair and running the comb through the underlying hair or between layers thereof, thus thinning and tapering the hair so as to make the same movement with the shape of the head.

20 30 In the modification illustrated in Figs. 7 and 8, a thin metal plate 23 has its upper and lower edges bent outwardly and thence toward each other to form retaining lips or flanges 24 and adjustably mounted on the plate with their ends arranged beneath said flanges, are three plates 25, 26 and 27.

25 40 Plates 25 and 26 carry posts 28, one of which is provided with an aperture 29 and the other with an undercut notch 30, which aperture and notch provide bearings for the pintles on the ends of the clamping plate.

45 Plate 27, which is positioned between plates 25 and 26, is provided on its outer face with a lug 31 that engages in the notches in the inner ends of the razor blades that are applied to the holder.

50 55 In the modified construction illustrated in Fig. 9, a plate 32, similar to the plate 10 has secured to the central portion of its flat face a longitudinally disposed metal strap 33, the ends of which are bent outwardly at right angles to form posts 34. One of these posts is provided with a pinte receiving aperture 35 and the other post with an undercut pinte receiving notch 36.

Thus it will be seen that I have provided a hair cutting attachment for combs that is relatively simple in construction, inexpensive of manufacture and very effective in performing the functions for which it is intended.

60 It will be understood that minor changes in the size, form and construction of the various

parts of my improved hair cutting and shaping attachment for combs may be made and substituted for those herein shown and described without departing from the spirit of the invention, the scope of which is set forth in the appended claims.

I claim as my invention:

1. A hair cutting and shaping attachment for combs, comprising a plate, lugs formed on one of the faces of said plate for engaging the outer ends of a pair of standard forms of thin flexible razor blades that are positioned on said plate, a lug projecting from the center of said plate for engaging the inner ends of the razor blades positioned on said plate, posts projecting from said plate on the same side with said lugs, which posts are adapted to project between the teeth of the comb to which the attachment is applied, a clamping member pivotally mounted on said posts and a hook formed on one end of said clamping member for engagement with the back of the comb to which the attachment is applied. 80 85 90

2. A hair cutting and shaping attachment for combs as set forth in claim 1 and with a comb engaging and clamping plate arranged between the pivoted end of said clamping member and the teeth of the comb to which the attachment is applied. 130

3. A hair cutting and shaping attachment for combs, comprising a plate adapted to receive a razor blade, a pair of posts projecting from said plate, which posts are adapted to project between the teeth of the comb to which the attachment is applied, bearings formed in said posts, a clamping member mounted in said bearings and a hook carried by said clamping member for engagement over the back of the comb to which the attachment is applied. 105 110 115

4. A hair cutting and shaping attachment for combs as set forth in claim 3 and a clamping plate positioned between the pivoted end of said clamping member and the teeth of the comb to which the attachment is applied, which clamping plate is provided with notches for accommodation of the posts projecting from the first mentioned plate. 115 120

5. In a hair cutting and shaping attachment for combs, a pair of separately formed plates adapted to be positioned on opposite sides of the teeth of a comb, posts projecting from one of said plates and adapted to pass between the teeth of the comb to which the device is applied, the other plate having notches for the reception of said posts, means on one of said plates for engaging the ends of a standard form of thin flexible razor blade, a clamping member pivotally connected to said posts and a hook on said clamping member for engaging over the back of the comb to which the device is applied. 125 130 135

ARTHUR H. MADORE.
